UNITED STATES PATENT OFFICE.

GOODWIN O. BISHOP, OF HANNIBAL, MISSOURI.

MOVABLE AND ADJUSTABLE POST AND PILE DRIVING MACHINE.

SPECIFICATION forming part of Letters Patent No. 250,336, dated December 6, 1881.

Application filed October 17, 1881. (No model.)

To all whom it may concern:
Be it known that I, GOODWIN O. BISHOP, a citizen of the United States, residing in Hannibal, in the county of Marion and State of Missouri, have invented a new and useful Improvement in Post and Pile Drivers; and I do hereby declare that the following is a full, clear, and exact description of the same, reference being had to the accompanying drawings, in ⁵ which—

Figure 1 is a rear elevation of the truck and frame. Fig. 2 is a side elevation of the same, and Fig. 3 is a sectional plan view thereof.

This invention has relation to post and pile ¹⁵ drivers; and it consists in the novel construction and arrangement of parts, as will herein-after be fully described, and pointed out in the claims.

Referring by letter to the accompanying ²⁰ drawings, A designates the truck-frame; B B, the supporting-wheels, and C the guide-wheel. From the truck-frame A rises an axially-adjustable frame, D, having the curved guide E near its lower end. The leads F F, ²⁵ for guiding the hammer G, are swiveled to the top of this frame D, and a ladder-brace, H, is hinged to the top of the frame D and connects at its bottom with an inclined frame, X, secured to the truck-frame in such a manner that ³⁰ the ladder-brace may be adjusted to keep the leads in a vertical position when the truck-frame is resting on inclined or uneven ground. The leads F are provided with a bracket, I, which engages the curved guide E. A pivot-³⁵ ed ratchet-arm, J, is connected to the leads and engages a dog, K, on the frame D, to hold the leads to their adjustment in a vertical position when one of the supporting-wheels rests on higher ground than the other one. A sliding evener, L, works on the truck-frame A, a tongue, M, and neck-yoke N being provided, to which the team may be hitched. A chain, O, connected with the hammer, runs over a pulley, P, at the top of the leads; thence down ⁴⁰ under a pulley, Q, in the truck-frame A, and is connected to the evener. The inclined frame X is provided with a shaft, R, carrying ratchet-wheels S, engaging straight racks T on the ladder-brace. A hand-wheel, U, at the end of ⁴⁵ the shaft R, is employed to adjust the frame D, by moving the ladder-brace either up or down, as may be necessary to keep the leads in a vertical position. A chain, V, provided with a

hook, V', is attached to the axle of the truck, and is employed to regulate the distance between the posts or piles, as is shown, by engaging the hook V' with the post last driven and moving the machine forward until the chain V becomes taut, and then driving another post and repeating the operation until ⁵⁵ the desired number of posts have been driven. The guide-wheel C at the front of the truck is for guiding the machine. The hammer is held by the nippers in the usual manner, and check-pieces near the top of the leads are employed ⁶⁰ to trip the nippers.

This machine may be readily drawn from place to place, and the team utilized to operate the hammer. It may be adjusted laterally and axially, to always keep the leads in a vertical position; and although I do not broadly claim a post or pile driver having these two ⁷⁰ adjustments, I do claim the special construction herein-after claimed.

Having thus fully described my invention, ⁷⁵ what I claim as new, and desire to secure by Letters Patent, is—

1. In a post and pile driving machine, the combination, with the truck-frame A, mounted on the wheels B B and C, of the frame D, hinged ⁸⁰ ladder-brace H, provided with the straight tracks T, the inclined frame X, and the ratchets S, and hand-wheel U on the shaft R, whereby the frame D is rendered axially adjustable, substantially as and for the purposes set forth. ⁸⁵

2. In a post and pile driving machine, the combination, with the axially-adjustable frame D, provided with the curved guide E, near its lower end, of the leads F, swiveled to the top of said frame and provided with the bracket I, ⁹⁰ near their lower ends for engaging the guide E, and the rack J and dog K, whereby the leads may be adjusted laterally within the frame D and be held to their adjustment, substantially as and for the purposes specified. ⁹⁵

3. In a post and pile driving machine, the combination, with the truck-frame A, carrying pulley a, axially-adjustable frame D, carrying pulley P near its top, and laterally-adjustable leads F, of the sliding evener L, chain O, and the hammer G, substantially as and for the purposes specified. ¹⁰⁰

GOODWIN O. BISHOP.
